UNITED STATES PATENT OFFICE.

FLOOR J. HAKKERS, OF PELLA, IOWA.

AUTO CHAIN LOCK.

Application filed April 7, 1922. Serial No. 550,376.

To all whom it may concern:

Be it known that FLOOR J. HAKKERS, a citizen of the United States of America, residing at Pella, in the county of Marion and State of Iowa, has invented new and useful Improvements in Auto Chain Locks, of which the following is a specification.

The object of the invention is to provide a simple and efficient construction of lock for connecting the extremities of the retaining chains of anti-skid or tire tread chains under conditions providing against the accidental loosening or unlocking thereof and hence the release and loss of the tire chains or the injury to the vehicle incident to the thrashing of the chains after the discovery of the looseness and before the car can be brought to a stop; and with this object in view the invention consists in a construction and combination of parts of which a preferred embodiment is shown in the accompanying drawings, wherein:

Figure 1 is a perspective view of a chain lock embodying the invention applied in the operative position to a retaining chain of typical or conventional form and showing the parts thereof in the locked position.

Figure 2 is a side view of the lock detached.

Figure 3 is a similar view showing the lock with the members thereof in the unlocking or chain releasing position.

Figures 4 and 5 are detail views respectively of the chain lock members.

The device consists essentially of pivotally connected members 10 and 11 of which the former is represented by a single flat leaf or plate and the latter by a plurality of side laterally spaced leaves or plates with an intervening interval corresponding approximately in thickness with the leaf forming the member 10, so that the member 10 may fold upon the common pivot 12 to lie between the planes of the leaves forming the member 11 and co-extensively therewith.

Each of the members is provided with a longitudinal slot of which that shown at 13 in the intermediate member is adapted for registration with that shown at 14 in the other member, when the members are in the folded or registering position, and each of said slots being provided at its outer end with an enlargement 13^a and 14^a constituting when in registration a joint seat for the terminal link or eye 15 at the free end of the chain 16. The pivot 12 connecting the mem-

bers of the lock also serves as a means of connecting the lock with the terminal link 17 at the other end of the chain and which is provided with coils 18 to engage said pivot which in the construction illustrated is in the form of a rivet and is terminally headed as indicated at 12^a.

In each of the leaves and in communication with the slot thereof there is formed a laterally directed and laterally accessible entrance throat of which that in communication with the slot 13 is indicated at 13^b while that which is in communication with the slot 14 is indicated at 14^b, said entrance throats thus being arranged at the inner ends of the slots or adjacent to the axis of movement of the leaves and close enough to the axis of movement or to the pivot forming said axis to be invaded or overlapped by the other leaf, said throats being formed in relatively opposite edges of the two leaves so that they are disposed in facing relation when the leaves are deflected as shown in Figure 3 to permit of engagement and disengagement of the terminal link or eye of the chain. In other words the throat in each leaf is spaced from the axis of movement of the leaves a distance less than half the width of the other leaf so that while the throats of the two leaves are in alignment transversely when the leaves are in the folded or closed position as will be noted by reference to Figures 1 and 2 and will assume a position of transverse registration as the leaves are pivotally moved to the angular position indicated in Figure 3, so that a link or eye 15 may be moved laterally of the leaf 11 through the transversely registering portions of the throats as the leaf 10 is pivotally moved to the position indicated in Figure 3, the throats are respectively closed against access of the link or eye thereto by the overlapping portions respectively of the other leaves, when the leaves reach the open position indicated in Figure 3, so that in order to re-engage the link or eye with the lock it is necessary to dispose the said link or eye, as indicated in Figure 3, in the angle between the leaves and then close or pivotally swing the leaves toward each other so that the link or eye will follow the transversely registering portions of the throats during the closing movement until it reaches a position engaging the transversely registering portions of the slots 13 and 14 from

whence it may readily pass into the seat formed by the transversely registering enlargements 13^a and 14^a. The overhanging or invading portion of the edge of each leaf thus constitutes a temporary closure for the throat of the other leaf when the leaves are in the open position and said throats can only be used as a means of permitting disengagement of the terminal link or eye of the chain when the latter is moved in conjunction with the opening movement of the leaves as above described, to maintain it in the transversely registering portions of the throat and hence in advance of the invading portion of the edge of the other leaf.

The side leaves constituting the member 11 are preferably struck from a single plate doubled or folded upon itself at one edge as shown at 19, and the extremity of this doubled portion constitutes a shoulder 20 forming a stop for engagement by an ear 21 formed on and projecting from the end of the intermediate leaf to limit the angular swinging movement thereof to the position indicated in Figure 3 which is necessary in order to permit of the introduction for engagement of the terminal link or eye 15 of the chain.

It will be observed that in the construction illustrated and as preferred in practice the entrance throats are disposed in oblique relation with the length of the leaves in which they are respectively formed and are disposed in substantially tangential relation with the axis of pivotal movement of the leaves so that as the leaves swing relatively about their pivot in the opening or closing movement thereof the entrance throats follow a common path or remain throughout in transverse registration to afford a passage

for the terminal link or eye of the chain which is to be secured.

Having described the invention, what is claimed as new and useful is:—

1. A chain lock having pivotally connected members consisting of flat leaves foldable edgewise or parallel with their planes and provided with longitudinal transversely registerable slots terminally forming seats for a terminal chain link or eye, said slots having laterally directed entrance throats each of which is invaded by the adjacent edge of the other leaf to constitute temporary closures for the throats when the leaves are in open position, the invading portions of the leaves gradually receding from the throats during the closing operation.

2. A chain lock having pivotally connected members consisting respectively of a flat leaf and a duality of spaced leaves having an intervening interval corresponding approximately to the thickness of the first leaf, the two members being foldable edgewise or parallel with their planes and provided with transversely registerable slots terminally forming seats for a terminal link or eye, said members being provided with laterally directed entrance throats disposed in oblique relation with the lengths of the leaves so that when in open position each entrance throat is invaded by the adjacent edge of the other leaf to provide a temporary closure for the throat gradually receding as the leaves are moved to folded position.

In testimony whereof he affixes his signature.

FLOOR J. HAKKERS.
